UNITED STATES PATENT OFFICE.

MINTON H. NEWELL, OF SAN FRANCISCO, CALIFORNIA, ASSIGNOR TO THE ALLOYS COMPANY, OF SAN FRANCISCO, CALIFORNIA, A CORPORATION OF CALIFORNIA.

PROCESS OF AND APPARATUS FOR MANUFACTURING METAL DUST.

Application filed September 13, 1921. Serial No. 500,369.

To all whom it may concern:

Be it known that I, MINTON H. NEWELL, a citizen of the United States, and a resident of the city and county of San Francisco, State of California, have invented a certain new and useful Process of and Apparatus for Manufacturing Metal Dust, of which the following is a specification.

The invention relates to a process of and an apparatus for manufacturing metal dust and particularly zinc dust.

An object of the present invention is to provide a process of and an apparatus for manufacturing metal dust, particularly zinc dust, of extreme and uniform fineness.

Another object of the invention is to provide an apparatus for maintaining the separation of and separately recovering the extremely fine metal dust and the larger particles of metal resultant from the condensation of metal vapor.

A further object of the invention is to provide means for collecting and congregating the coarser particles without admitting air to the condenser.

The invention possesses other advantageous features, some of which, with the foregoing, will be set forth at length in the following description, where I shall outline in full, the process of my invention and that form of apparatus embodying my invention which I have selected for illustration in the drawings accompanying and forming part of the present specification. In said drawings I have shown one form of apparatus embodying my invention, but it is to be understood that I do not limit myself to such form, since the invention, as set forth in the claims, may be embodied in a plurality of forms.

Referring to said drawings:

Figure 1 is a vertical section through one form of apparatus embodying my invention.

Fig. 2 is an elevation of the scraper mechanism, parts thereof being broken away to reduce the size of the figure.

Fig. 3 is a vertical section through the scraper handle seal.

In the manufacture of zinc dust, by the method which I employ, spelter, zinc dross or other zinc containing material, is heated to vaporization in a retort and the vapors discharged into a condensing chamber in which they are condensed. The condenser

is usually made of sheet metal and its outer surface is exposed to the air to permit the radiation of heat, and consequently the walls of the condenser are comparatively cool. During the time that the vapor is present in the condensing chamber, its temperature is falling, and I have found that to produce zinc dust of extreme fineness, that the vapor must be comparatively cool before it condenses or before it comes into contact with the cool walls of the condenser. Some of the hot vapor however, contacts with the cool chamber walls before it becomes cool, with the result that metallic droplets of various sizes are formed in the condenser. The presence of these droplets is undesirable in the zinc dust and I have provided a process and an apparatus for preventing these metallic droplets from mixing with the fine zinc dust. These droplets are formed principally in that region of the condenser adjacent the inlet of the hot vapors from the retort, since in this region the walls of the condenser are closer to the mouth of the retort than in other portions of the condenser. The amount of metallic droplets formed is reduced by shaping the condenser, with relation to the discharge outlet of the retort, so that the vapors are considerably cooled before they contact with the adjacent walls of the condenser, but the formation of the metallic droplets in this region has not been entirely obviated. In accordance with my invention I collect these metallic droplets, or the major portion of them, separately from the larger portion of the zinc dust and maintain this separation, so that the zinc dust is of uniformly extreme fineness. Some fine zinc dust is collected with the metallic droplets, but the main body of the fine zinc dust is practically free from the metallic droplets.

The spelter, zinc dross or other zinc bearing material, is vaporized in a retort 2, which is arranged within the furnace 3, the neck 4 of the retort extending through and forming a tight joint with the front wall 5 of the furnace, to prevent the entry of gases of combustion into the condenser. From the retort, which is preferably disposed in an inclined position, the hot zinc vapors discharge into the condenser 6, through the hood 7, forming an extension of the condenser and forming tight joints 110

2

with the furnace walls. The condenser and the hood are preferably formed of sheet metal, and the condenser is preferably cylindrical in shape and the hood is preferably 5 rectangular its height being greater than its width. The mouth of the retort is arranged adjacent the bottom of the hood and the height of the hood is such that the top wall 8 thereof is spaced sufficiently from the 10 mouth of the retort, to permit the hot vapors from the mouth, to cool before they rise into contact with the top, to minimize the formation of droplets. The rear wall 9 of the hood is set back, preferably behind 15 the plane of the front surface of the furnace wall 5, to minimize the contact of the rising hot vapors therewith. The hood is preferably disposed adjacent the lower part 20 of the condenser so that a clear condensing space is provided in the the condenser above the hood.

The condenser is provided with a conical bottom 13 in which the greater portion of the extremely fine zinc dust collects and at 25 its lower end is provided with an inclined discharge chute 14, normally closed by the hinged gate 15. A separate receptacle is provided for collecting the metallic droplets mixed with whatever fine dust may 30 deposit with them and since these droplets form principally and almost entirely adjacent the mouth of the retort, or in the present construction, in the hood 7, this separate receptacle is arranged to receive and collect 35 the material deposited in the hood. Disposed in the conical bottom 13 on that side adjacent the hood is a transverse inclined wall 16 which extends up to the hood and above the plane of the bottom wall 17 there- 40 of, forming with a portion of the conical bottom, a receptacle 18, separate from the cone 13 and opening into the hood at the bottom thereof. The receptacle 18 is pro- 45 vided at its lower end with a chute 19 pass- 50 ing vertically through the wall of the conical bottom, terminating at its lower end in an inclined portion 21 normally closed by the hinged gate 22. By virtue of the provi- 55 sion of two independent collecting chambers, the droplets are separately collected and the main body of the fine zinc dust is practically 60 free from droplets.

The zinc vapor may be condensed in the presence of a limited or controlled amount 55 of air or oxygen, introduced into the condenser and first contacting with a comparatively cool portion of the vapor, and when air is to be admitted to the condenser, it is 60 provided at a point remote from the mouth 65 of the retort, with a controllable aperture 23, through which air in regulated quantity may be introduced, but when desired, this aperture may be eliminated or closed and the condenser practically sealed against the 65 introduction of air. Whether the condenser

is to be sealed against the inflow of air or whether air is to be admitted in controllable quantities depends upon the product it is desired to produce.

The greater portion of the material 70 condensed in the hood 7, deposits on the bottom wall 17 thereof and means are provided for moving this deposited material into the receptacle 18. The means employed for this purpose is a scraper or hoe 24 provided with 75 an operating handle 25 extending to the exterior of the condenser. The joint between the handle and the wall of the condenser is sealed to prevent the inflow of air and the sealed joint is flexibly mounted to permit 80 the handle to assume varying inclinations when the scraper is operated. Secured to the wall of the condenser opposite the retort, is a diaphragm or flexible disc 26 of imper- 85 ous material, to the center of which is se- 90 cured a stuffing box 27 through which the handle 25 passes. The handle is movable longitudinally through the stuffing box, the joint being sealed by the packing 28 and the stuffing box is flexibly mounted so that it is 95 free to assume various positions.

Means are provided for controlling the movement of the scraper, so that it will rise and pass over the material collected on the wall 17 on its back stroke, so that it will 100 not strike and injure the mouth of the retort and so that it will move horizontally over the wall 17 on its forward stroke, scraping the collected material into the receptacle 18. Pivoted to a bracket 31 secured to the wall 16 are a pair of parallel contiguous links 32, each provided with a longitudinal slot 33 terminating at its end in a transverse pocket 34. The handle 25 of the scraper is provided with a cross pin 35 engaging in 105 said slots, and movable into said pockets. When the scraper is in its foremost position, the links are forwardly inclined, as shown in full lines in Fig. 2 and the cross pin seats in the pockets 34. When the handle is 110 pushed backward, the pin remains in the pockets, causing the links to rock on their pivots, moving the scraper through the curved path indicated by the dotted line, to 115 its rearward position, as shown. In this position, the links move to free the pin from the pockets, disposing it in the slots 33, so that on the forward movement of the handle, the pin slides in the longitudinal slots and the scraper moves horizontally over the 120 wall 17 scraping the material into the receptacle 18.

I claim:

1. The process of manufacturing metal dust, comprising vaporizing the metal, condensing the vapor to metal dust and solid metallic droplets and collecting the metal dust separate from the droplets.

2. The process of manufacturing metal dust, comprising vaporizing the metal, in-

roducing the vapor into a condensing chamber wherein it condenses to metal dust and solid metallic droplets, collecting the dust separate from the droplets and separately removing the dust from the condensing chamber.

3. The process of manufacturing metal dust, comprising vaporizing the metal, condensing the vapor in the presence of a limited regulated supply of oxygen, whereby metal dust and solid metallic droplets are formed and collecting the metal dust free from the droplets.

4. The process of manufacturing metal dust, comprising vaporizing the metal, introducing the vapor into a condenser where in the hot vapor condenses to solid metallic droplets adjacent the vapor inlet and condenses to dust remote from the vapor inlet and collecting and recovering the dust and the droplets substantially separate.

5. The process of manufacturing metal dust, comprising vaporizing the metal, supplying to the vapor a limited amount of air, first contacting with a comparatively cool portion of the vapor, condensing the vapor in the presence of said supply of air whereby metal dust and metallic droplets are precipitated and collecting the dust substantially separate from the droplets.

6. The process of manufacturing metal dust, comprising vaporizing the metal, condensing the vapor partly to metal dust and partly to solid metallic droplets and separately collecting and recovering the metal dust substantially free from droplets.

7. An apparatus for manufacturing metal dust comprising a retort in which the metal is vaporized, a condensing chamber of heat conducting material into which substantially all of the vapor is introduced and in which it condenses, a collecting chamber adapted to receive material condensed adjacent the vapor inlet and a collecting chamber adapted to receive material condensed at other portions of the condensing chamber whereby said materials are maintained separated.

8. An apparatus for manufacturing metal dust comprising a retort in which the metal is vaporized, an air cooled condensing chamber into which substantially all of the vapor is introduced and in which it condenses to metal dust and solid metallic droplets and a collecting chamber for collecting the dust substantially separately from the droplets.

9. An apparatus for manufacturing metal dust comprising a retort in which the metal is vaporized, an air cooled condensing chamber into which substantially all of the vapor is introduced and in which it condenses to metal dust and solid metallic droplets, a collecting chamber for the dust and a collecting chamber for the droplets.

10. An apparatus for manufacturing metal dust comprising a retort in which the metal is vaporized, an air cooled condensing chamber into which substantially all of the vapor is introduced and in which it condenses to metal dust and solid metallic droplets and means for collecting and recovering the dust substantially free from droplets.

11. An apparatus for manufacturing metal dust comprising a retort in which the metal is vaporized, an air cooled condensing chamber into which substantially all of the vapor is introduced and in which it condenses to metal dust and solid metallic droplets and means for substantially separately collecting the dust and the droplets.

12. An apparatus for manufacturing metal dust comprising a retort in which the metal is vaporized, an air cooled condensing chamber into which substantially all of the vapor is introduced and in which it condenses to metal dust and solid metallic droplets, a large cone shaped bottom on the condensing chamber for collecting the dust and a small collecting chamber for the droplets.

13. An apparatus for manufacturing metal dust comprising a retort in which the metal is vaporized, a condensing chamber into which the vapor is introduced and in which it condenses to metal dust and solid metallic droplets, a collecting chamber for the dust, a collecting chamber for the droplets and separate gate controlled discharge apertures on said collecting chambers, through which the collected material may discharge by gravity.

14. An apparatus for manufacturing metal dust comprising a retort in which the metal is vaporized, a condensing chamber in which the vapor condenses to metal dust, a hood interposed between the retort and the condensing chamber in which a portion of the vapor condenses to metallic droplets, a collecting chamber for the dust, a collecting chamber for the droplets and means for moving the precipitated droplets into said second collecting chamber.

15. An apparatus for manufacturing metal dust comprising a retort in which the metal is vaporized, a condensing chamber in which the vapor condenses to metal dust, a hood interposed between the retort and the condensing chamber in which a portion of the vapor condenses to metallic droplets, a collecting chamber for the dust, a collecting chamber for the droplets and a scraper operable from the exterior of the condenser for moving the precipitated droplets into said second collecting chamber.

16. An apparatus for manufacturing metal dust comprising a retort in which the metal is vaporized, a condensing chamber in which the vapor condenses to metal dust,

- a hood interposed between the retort and the condensing chamber in which a portion of the vapor condenses to metallic droplets, a collecting chamber for the dust, a collecting chamber for the droplets, a scraper operable from the exterior of the condenser for moving the precipitated droplets into said second collecting chamber and means for controlling the movement of said scraper.
10. 17. An apparatus for manufacturing metal dust comprising a retort in which the metal is vaporized, a condensing chamber in which the vapor condenses to metal dust, a hood interposed between the retort and the condensing chamber in which a portion of the vapor condenses to metallic droplets, a collecting chamber for the dust, a collecting chamber for the droplets, a scraper operable from the exterior of the condenser for moving the precipitated droplets into said second collecting chamber and a flexible air-tight connection between the scraper and the wall of the condensing chamber.
15. 18. An apparatus for manufacturing metal dust comprising a retort in which the metal is vaporized, a condensing chamber in which the vapor condenses to metal dust, a hood interposed between the retort and the condensing chamber in which a portion of the vapor condenses to metallic droplets, a collecting chamber for the dust, a collecting chamber for the droplets, a scraper for moving the precipitated droplets into said second collecting chamber, a handle on said scraper, a diaphragm disposed in the wall of the condensing chamber, a stuffing box carried by said diaphragm and a handle on said scraper extending through said stuffing box.
20. 19. An apparatus for manufacturing metal dust comprising a retort in which the metal is vaporized, a condensing chamber in which the vapor condenses to metal dust, a hood interposed between the retort and the condensing chamber in which a portion of the vapor condenses to metallic droplets, a collecting chamber for the dust, a collecting chamber for the droplets, a scraper for moving the precipitated droplets into said second collecting chamber, a handle on said scraper and means for causing a backward movement of the handle to move the scraper in a vertical arc.
25. In testimony whereof, I have hereunto set my hand.

MINTON H. NEWELL.
